(57) **CLAIM**

The ornamental design for a sound bar, as shown and described.

DESCRIPTION

FIG. 1 is a front, right and top perspective view of a first embodiment of a sound bar, showing my new design; FIG. 2 is a rear, left and bottom perspective view thereof; FIG. 3 is a front, right and top perspective view in use state thereof;

FIG. 4 is a front view thereof;

FIG. 5 is a rear view thereof;

FIG. 6 is an enlarged left side view thereof;

FIG. 7 is an enlarged right side view thereof;

FIG. 8 is a top plan view thereof; and

FIG. 9 is a bottom plan view thereof.

FIG. 10 is an enlarged view of portion 10 of FIG. 1 thereof; FIG. 11 is an enlarged view of portion 11 of FIG. 1 thereof; FIG. 12 is a front, right and top perspective view of a second embodiment of a sound bar;

FIG. 13 is a rear, left and bottom perspective view thereof; FIG. 14 is a front view thereof;

FIG. 15 is a rear view thereof;

FIG. 16 is a front, right and top perspective view in use state thereof;

FIG. 17 is an enlarged left side view thereof;

FIG. 18 is an enlarged right side view thereof;

FIG. 19 is a top plan view thereof;

FIG. 20 is a bottom plan view thereof;

FIG. 21 is an enlarged view of portion 21 of FIG. 12 thereof; and,

FIG. 22 is an enlarged view of portion 22 of FIG. 12 thereof. The broken lines shown in the drawings illustrate portions of the sound bar that form no part of the claimed design. The dot-dash broken lines depict the boundaries of the enlargements that form no part of the claimed design.

1 Claim, 22 Drawing Sheets
